[57] ABSTRACT

In a mass-spectrometer of the double focussing type, output ions from an electric field analyzer are applied to a magnetic field analyzer so constructed that the condition indicated by the following equation,

$$\cos\epsilon' \cos\epsilon'' = \sin(\phi_m' - \epsilon' - \epsilon'')$$

is satisfied therein, where ϕ_m' is the deflection angle of the magnetic field analyzer, ϵ' is the angle of incidence of the input ions with respect to the magnetic field analyzer and ϵ'' is the angle of divergence of the output ions focussed at the outside of the magnetic field analyzer.

MASS-SPECTROMETER OF DOUBLE FOCUSSING TYPE

BACKGROUND OF THE INVENTION

This invention relates to the improvement of a mass-spectrometer of the double focussing type.

As is well known, a conventional mass-spectrometer of the double focussing type developed by Mattauch and Herzog is so constructed that ions having the same velocity and direction can be focussed on the same plane by an electric field analyzer and a magnetic field analyzer so as to attain a desired mass-analysis. Such a device is described, for example, in *Mass Spectrometry* by R. I. Reed, Academic Press, London and New York, 1965. In this known device, since ions are focussed on the end face of said magnetic field analyzer, when ions are required to be detected electronically, an ion collector is disposed at a position where the ions passing through an orbit having a maximum radius are focussed by scanning the magnetic field.

Therefore, the position of the ion collector is on the end face of said magnetic field analyzer and also a slit disposed in front of the ion collector must be disposed on the end face of said magnetic field analyzer.

However, it is not easy to provide such an arrangement. Moreover, since an ion detector, such as, for example, an electron multiplier, is disposed adjacent to the magnetic field so as to be connected to the output of said ion collector, it is necessary to magnetically shield the ion detector; however, it is difficult to completely attain such magnetic shielding.

Besides, in the case where ions are to be detected by using a photographic plate, this plate must be disposed on the end face of said magnetic field analyzer. Therefore, when it is intended to carry out ion detection by alternately changing the photographic plate and the magnetic field scanning as described above, this changing manipulation and its mechanism become very complicated.

SUMMARY OF THE INVENTION

An object of the invention is to provide a mass-spectrometer wherein the focussing point of the ions is located at the outside of the magnetic field analyzer except the end face thereof.

Another object of the invention is to simplify the changing manipulation and its mechanism in the mass-spectrometer.

A further object of the invention is to make it easy to arrange an electric detecting means in the magnetic field analyzer.

A still further object of the invention is to eliminate undesirable influences upon said detecting means due to magnetic field variation.

In order to realize the above objects, a mass-spectrometer of the invention is so constructed that the condition indicated by the following equation

$$\cos\epsilon' \cos\epsilon'' = \sin(\Phi_m' - \epsilon' - \epsilon'')$$

is satisfied therein, where Φ_m' is a deflection angle of the magnetic field produced by the magnetic field analyzer, ϵ' is the angle of incidence of the input ions with respect to the magnetic field analyzer and ϵ'' is the angle of divergence of the output ions focussed at the outside thereof.

BRIEF DESCRIPTION OF THE DRAWINGS

FIG. 1 is a schematic diagram showing a conventional mass-spectrometer of the double-focussing type; and

FIG. 2 is a schematic diagram showing an embodiment of the invention.

DESCRIPTION OF THE PREFERRED EMBODIMENTS

Firstly, the principle of a mass-spectrometer of the double focussing type as developed by Mattauch and Herzog will be explained; however, since the construction and operation of said mass-spectrometer are well known, as evidenced by the aforesaid reference and other literature, this description of the known system is limited to the extent required to provide an understanding of the invention.

FIG. 1 shows a basic construction of the above-mentioned known mass-spectrometer. In FIG. 1, numeral 1 is an ion source, numeral 2 is an electric field analyzer, numeral 3 is a magnetic field analyzer, numeral 4 is a photographic plate, numeral 5 is an ion collector, numeral 6 is a slit, and numeral 7 is an electron multiplier.

The photographic plate 4 is disposed on the end face AA' of the magneti field magnetic 3 to detect ions focused thereon. The ion collector 5 is disposed at a focal point A on an orbit 8 having the maximum radius r_m .

As mentioned above, the focal point of the ions is located on the end face AA' and the reason for this will be explained by the following. In said mass-spectrometer, the focal length f_e of the electric field produced by the electric field analyzer 2, the distance g_e between the input or output side of said analyzer 2 and its focal point, the focal length f_m of the magnetic field produced by the magnetic field analyzer 3, and the distance g_m between the input or output side of said analyzer 3 and its focal point are indicated, respectively, by the following equations:

$$f_e = (r_e / \sqrt{2}) (1 / \sin \sqrt{2} \phi_e) \quad (1)$$

$$g_e = (r_e / \sqrt{2}) \cdot \cot \sqrt{2} \phi_e \quad (2)$$

$$f_m = r_m \cdot (1 / \sin \phi_m) \quad (3)$$

$$g_m = r_m \cdot \cot \phi_m \quad (4)$$

where r_e is the radius of the ion orbit in the electric field produced by the electric field analyzer, ϕ_e is the deflection angle of the electric field, r_m is the radius of the ion orbit in the magnetic field produced by the magnetic field analyzer, and ϕ_m is the deflection angle of the magnetic field.

Moreover, in this case, the multiplication factor M_e of the electric field analyzer and the multiplication factor M_m of the magnetic field analyzer are indicated respectively by the following equations:

$$M_e = (f_e/g_e - l_e')$$

(5)

$$M_m = (f_m/g_m - l_m')$$

(6)

where l_e' is the distance between a first image point of the ion source 1 (an ion emission point of the ion source 1) and the input side of the electric field analyzer 2, and l_m' is the distance between a second image point focussed by the electric field analyzer and the input side of the magnetic field analyzer 3. This second image point, in general, exists between both said analyzers, but in said mass-spectrometer developed by Mattauch-Herzog, l_m' becomes infinite since ions do not focus at a point between both said analyzers, but run in parallel to each other.

Therefore l_m' is, in general, indicated by the following equation:

$$l_m' = \Delta - l_e'' = \Delta - [g_e - (f_e^2/g_e - l_e')]$$

(7) 25

where Δ is the distance between both said analyzers and l_e'' is the distance between the output side of the electric field analyzer 2 and the second image point.

The double focussing condition of a conventional mass-spectrometer of the double focussing type is indicated by the following equation:

$$r_e (1+M_e) = r_m [1 + (1/M_m)]$$

(8) 35

When this condition is satisfied, ions having the same velocity and direction can be focussed. At this time, a total multiplication factor M is equal to the product of M_e by M_m .

$$M = M_e \cdot M_m$$

(9)

In said mass-spectrometer developed by Mattauch and Herzog, the double focussing condition is satisfied by attaining the following condition: $M_e \rightarrow \infty M_m \rightarrow 0$

(10)

In order to attain the condition $M_e \rightarrow \infty$, it is necessary to cause g_e to be nearly equal to l_e' . Namely, the first image point must be positioned at the focal point of the electric field analyzer 2. Consequently, as is apparent from the equation (7), l_m' becomes infinite so that the ion beam does not focus at a point between both of the analyzers as mentioned above, and thus, the second image point does not exist therebetween. Moreover, at this time, as is apparent from equation 6, the condition $M_m \rightarrow 0$ is satisfied.

Besides, since g_e becomes nearly equal to l_e' , l_m' is practically determined by the following equation:

$$l_m' \approx (f_e^2/g_e - l_e')$$

(11)

Thus, l_m' can be regarded as having no relation to Δ , so that it can be selected to be any desired distance. In this case, the deflection angles ϕ_e and ϕ_m of both said analy-

zers are determined in such a manner as to satisfy the condition of the equation 10 as follows. The following equation:

$$1/M_m = (f_e/f_m) M_e$$

(12)

is derived from the equations 5, 6, and 9. By substituting $1/M_m$ in the equation 8 for this equation 12, the equation

$$1 + M_e = (r_m/r_e) [(1 + (f_e M_e/f_m))]$$

(13)

is obtained. In this equation 13, since M_e becomes infinite, and f_e and f_m are finite, it can be regarded that the equation

$$(r_m/r_e) \cdot (f_e/f_m) = 1$$

(14)

is approximately realized.

Therefore, the equation

$$[\sin \phi_m / (\sqrt{2} \sin \sqrt{2} \phi_e)] = 1$$

(15)

can be derived from the equations 1, 3 and 14, and thus if $\phi_m = 90^\circ$, the electric field analyzer must be designed to have the deflection angle $\phi_e = 31^\circ 51'$. In this case, as is apparent from equation 4, g_m is zero. That is, the focussing point of ions by the magnetic field analyzer falls on the end face AA' thereof, and thus many defects occur as mentioned above.

According to the invention, for the purpose of facilitating a measurement by the magnetic field scanning method, the magnetic field analyzer in the mass-spectrometer of the double focusing type is so constructed as to cause the focal point of the ions to be located outside of said analyzer, as shown in FIG. 2. By generalizing the equations representing the focal length f_m and other factors in the Mattauch - Herzog case, the following equations are obtained:

$$f_m = r_m' [\cos \epsilon' \cos \epsilon''] / \sin (\Phi_m' - \epsilon' - \epsilon'')$$

$$g_m' = r_m' [\cos \epsilon' \cos (\phi_m - \epsilon'') / \sin (\phi_m' - \epsilon' - \epsilon'')]$$

$$g_m'' = r_m' [\cos \epsilon'' \cos (\phi_m - \epsilon'') / \sin (\phi_m' - \epsilon' - \epsilon'')]$$

(18)

where g_m' is the distance between the input side of the magnetic field analyzer and the input side focal point thereof, g_m'' is the distance between the output side of the magnetic field analyzer and the output side focal point thereof, r_m' is the radius of the ion orbit in the magnetic field produced by the magnetic field analyzer when it is operated in accordance with the magnetic scanning method, Φ_m is the deflection angle of the magnetic field in accordance with the magnetic scanning method, ϵ_m' is the angle of incidence of the input ions with respect to the normal n_i to the input side of the magnetic field analyzer and ϵ'' is the angle of divergence of the ions with respect to the normal n_o to the output side of the magnetic field analyzer.

Assuming now that ion beam is induced to the input side of the magnetic field analyzer at an angle of 90° namely $\epsilon' = 0$, in the same way as the Mattauch - Herzog case, the following equation

$$\sqrt{2} \sin \sqrt{2} \phi_e = [\sin (\phi_m' - \epsilon'') / \cos \epsilon'] \quad (19)$$

is derived from the equations 1 and 14. In the equation 19, as mentioned above, if $\phi_e = 31^\circ 51'$, the left side thereof becomes equal to 1 and thus the following equation

$$\cos \epsilon'' = \sin (\phi_m' - \epsilon'') \quad 10 \quad (20)$$

is obtained. By substituting $\cos \epsilon''$ in the equation 18 for the equation 20, the equation 18 is changed into the following equation:

$$g_m'' = r_m' \cos \phi_m' \quad 15 \quad (21)$$

As is apparent from equation 21, the condition $0 \leq g_m'' \leq r_m'$ is realized and thus g_m' does not become substantially zero. Therefore, if, for example, Φ_m' is set to be 60° , r_m' becomes equal to 360_{mm} and ϵ'' and g_m'' become about -15° and 180_{mm} respectively. This means that when ions are intended to be detected by means of the magnetic scanning method, as shown in FIG. 2, if the magnetic field analyzer 3 is adjusted to have a deflection angle ϕ_m of 60° , ions induced to the input side of the magnetic field analyzer with the right angle therebetween pass through the orbit having a radius $r_m' = 360_{mm}$, and are focussed at a point outside of the magnetic field analyzer with an output angle ϵ'' of about -15° , so that the ion collector 5 can be disposed at the focussed point where g_m' is 180_{mm} distant from the magnetic field analyzer. In this case, if the photographic plate method is intended to be employed, the magnetic field analyzer 3 is adjusted to cause the deflection angle ϕ_m thereof to be equal to 90° in the same way as the conventional construction and the photographic plate 4 is disposed on the end face AA' of the magnetic field analyzer.

In the above case, the input angle ϵ' is set to be zero. If ϵ' is not zero, the equations 20 and 21 are changed into the following equations:

$$\cos \epsilon' \cos \epsilon'' = \sin (\phi_m' - \epsilon' - \epsilon'') \quad 45 \quad (22)$$

$$g_m'' = r_m' [\cos \epsilon'' \cos (\phi_m - \epsilon') / \sin (\phi_m' - \epsilon' - \epsilon'')] \quad 50 \quad (23)$$

Therefore, even if ϵ' is not zero, g_m' does not become zero. As described above, once the magnetic field analyzer is constituted to obtain the condition indicated by equation 22, the double focussing condition can be attained and at the same time it can be greatly simplified to exchange from the magnetic scanning method into the photographic plate method and vice versa.

What is claimed is:

1. A mass-spectrometer of the double focussing type including

an ion source providing ions to be analyzed, an electric field analyzer supplied said ions to be analyzed and having means producing an electric field for analyzing the ions supplied thereto by means of the electric field,

a magnetic field analyzer disposed so as to be supplied with the ions from the output of the electric field analyzer and having means producing a magnetic field for analyzing the ions supplied thereto by means of the magnetic field, and

a photographic plate disposed on an end face of said magnetic field analyzer so as to allow the ions in said magnetic field analyzer to be focussed onto the photographic plate when said mass-spectrometer is operated in accordance with a photographic plate method,

wherein the improvement comprises:

means for regulating the magnetic field generated in said magnetic field analyzer, when said mass-spectrometer is operated in a magnetic field scanning method, to focus the ions at a position spaced from the end face of said magnetic field analyzer so as to produce a magnetic field of a magnitude different from that produced when said mass-spectrometer is operated in accordance with the photographic plate method; and

detector means disposed at said position spaced from the end face of said magnetic field analyzer and outside thereof where the ions are focussed by the magnetic field of the magnitude produced when said mass-spectrometer is operated in the magnetic field scanning method, the mutual disposition of said electric field analyzer, said magnetic field analyzer and said detector means as well as the magnitude of the magnetic field when said mass-spectrometer is operated in the magnetic field scanning method being defined by the relationship

$$\cos \epsilon' \cos \epsilon'' = \sin (\phi_m' - \epsilon' - \epsilon'')$$

where

ϕ_m' is the deflection angle by the magnetic field produced by said magnetic field analyzer when said mass-spectrometer is operated in the magnetic field scanning method,

ϵ' is the angle of incidence of ions to be analyzed with respect to said magnetic field analyzer, and

ϵ'' is the angle of divergence of analyzed ions with respect to said magnetic field analyzer, whereby said detector means can be less affected by the magnetic field.

2. A mass-spectrometer of the double focussing type capable of being operated in accordance with both photographic plate method and a magnetic field scanning method comprising

an ion source providing ions to be analyzed, an electric field analyzer to which the ions to be analyzed are supplied including means for producing an electric field for analyzing the ions supplied thereto,

a magnetic field analyzer to which the ions derived from said electric field analyzer are supplied including means for producing a magnetic field for analyzing the ions supplied thereto,

a photographic plate disposed on an end face of said magnetic field analyzer and used when said mass-spectrometer is operated in accordance with the photographic plate method for detecting the analyzed ions, and

an ion detector used when said mass-spectrometer is operated in accordance with the magnetic field scanning method for detecting the analyzed ions,

said magnetic field analyzer including means for regulating said magnetic field producing means, when said mass-spectrometer is operated in the magnetic field scanning method to focus the ions at a position spaced from the end face of said magnetic field analyzer so that the magnetic field has a magnitude different from that produced when said mass-spectrometer is operated in the photographic plate method, and
 said ion detector being disposed at said position spaced from the end face and outside of said magnetic field analyzer so as to satisfy the following equation

$$\cos \epsilon' \cos \epsilon'' = \sin (\phi_m' - \epsilon' - \epsilon'')$$

5

10

15

where

ϕ_m' is the deflection angle by the magnetic field of the magnitude produced when said mass-spectrometer is operated in the magnetic field scanning method,
 ϵ' is the angle of incidence of ions input from said electric field analyzer with respect to said magnetic field analyzer, and
 ϵ'' is the angle of divergence of the ions output from said magnetic field analyzer with respect thereto, whereby said ion detector can be less affected by the magnetic field.
